UNITED STATES PATENT OFFICE

2,535,578

RADIO TUBE SOCKET

Bengt J. Johanson, Chicago, Ill., assignor to
Cinch Manufacturing Corporation, Chicago,
Ill., a corporation of Illinois

Application August 9, 1945, Serial No. 609,732

2 Claims. (Cl. 173—328)

1

The present invention relates to sockets such as those for mounting pronged vacuum tubes and the like, and aims generally to improve existing sockets of the type wherein the tube prongs are locked in the socket.

One of the primary objects of the invention is the provision of an improved and novel socket having a locking member which also serves as a grounding wire terminal.

A further object of the invention is the provision of a lock-in type socket of such construction that accurate spacing between the top of the socket and the locking point is assured.

The above and other objects of the invention will be readily understood by those skilled in the art from a consideration of the accompanying drawings and annexed specification illustrating and describing a preferred embodiment of the invention.

In the drawings

Fig. 1 is a side elevation of a portion of a tube and the socket therefor embodying the invention;

Fig. 2 is a vertical sectional view of the socket as taken on the line 2—2 of Fig. 1, a portion of the tube and the grounding prong thereof being shown in elevation;

Fig. 3 is a bottom plan view of the socket illustrated in Fig. 1;

Fig. 4 is a detail perspective view of the socket-locking sleeve; and

Fig. 5 is a detail perspective view of the socket-locking spring.

Referring to the drawings, the socket is conveniently formed of a body 10 of suitable insulating material to provide a support for a vacuum tube 11 or the like of the type having a plurality of prongs for engaging contacts (not shown). Such contacts usually are provided with wiring terminals 12 whereby the tube circuits may be electrically connected to circuits of the apparatus in which it is used.

Many tubes are provided with a central positioning prong 13 which may be of such cross sectional shape as to insure proper contacting engagement of the tube prongs (not shown) and contacts 12, and this positioning prong may also serve as a ground terminal to be connected to a ground circuit.

According to the invention, the socket is of the lock-in type and is provided with a locking device or fastened part to lockingly engage the positioning prong 13.

The socket may be provided with a central bore 15 in which is fitted a sleeve 16 of suitable insulating material as illustrated. The sleeve 16

2

is preferably of greater length than the thickness of the socket from the top to the bottom surface thereof, so as to provide an extension beyond the socket for the locking device. Instead of the sleeve being separate the extension may be moulded integral with the body of the socket.

The lower portion or extension of the locking sleeve 16 is shaped to provide a support or mounting for a locking spring 20 which conveniently may be of double P-shape as illustrated in Fig. 5. This construction of fastener or locking element provides a U-shaped base portion 21 and spaced opposed locking fingers or bars 22 adapted to lockingly engage in a notched or grooved end 23 of the prong 13. The legs of the P-shaped locking device may be formed as angular extensions 24 of the bars 22 and serve as grounding terminals for connecting with an electric conductor.

The locking spring 20 is supported in the pre-shaped end of the sleeve 16 which may be substantially C-shaped and formed by stabbing off opposite sides of the end of the sleeve 16 and then gapping one of the legs near the end of the sleeve as at 25. This provides a base 26 for supporting the base 21 of the locking spring.

It will be apparent that the spring wire locking device 20 may be pre-assembled with the sleeve 16 and the two thereafter assembled with the socket body 10 as a unit. The portions or strands 22 of the locking device are supported in spaced relation with respect to the base and are laterally expandable in a plane normal to the axis of the sleeve for snap-locking engagement in a groove or seat 23 in the tube prong 13.

The above described construction provides a simple, economical socket for effectively and efficiently locking a pronged tube or the like in place in the socket while insuring an accurate predetermined distance or spacing between the top face of the socket and the locking part.

Although I have illustrated and described preferred forms of my invention, I do not wish to be limited thereby because the scope of my invention is best defined by the following claims.

I claim:

1. A socket for pronged vacuum tubes and the like comprising a socket body of insulating material having a prong-receiving bore extending through said body between opposite faces, spaced arms extending outwardly from one face of said body on opposite sides of said bore, a fastener-supporting base connected to one of said arms and underlying one end of said bore, said base having a supporting surface spaced from and disposed substantially parallel to the adjacent face

of said body, and a fastening device mounted on said base, said fastening device comprising a pair of substantially parallel wire strands connected together by a resilient bight, said resilient bight and portions of the strands adjacent thereto forming a mounting portion in engagement with said supporting surface, continuing portions of said strands being reversely bent to form a prong-engaging portion disposed in opposed relation to said mounting portion and in tensioned engagement with said adjacent face of said body, and then angularly bent to form a terminal portion extending angularly from said prong-engaging portion, the strands of said prong-engaging portion being disposed on opposite sides of said arms to assist in maintaining said fastening device in mounted position on said supporting base.

2. A socket for pronged vacuum tubes and the like comprising a socket body of insulating material having a bore extending through said body between opposite faces, a prong-receiving sleeve fitted in said bore, fastener-supporting means at one end of said sleeve comprising a pair of extensions of portions of the walls of said sleeve at opposite sides thereof and an element projecting from the end of one of said extensions presenting a supporting surface spaced from and substantially parallel to and underlying the end of said sleeve, the other of said extensions being shorter than said one extension and having its end spaced from said supporting surface of said projecting element, and a fastening device mounted on said supporting surface, said fastening device comprising a pair of substantially parallel wire strands connected together by a resilient bight,

said resilient bight and portions of the strands adjacent thereto forming a mounting portion in engagement with said supporting surface, continuing portions of said strands being reversely bent to form a prong-engaging portion disposed in opposed relation to said mounting portion and in tensioned engagement with said end of said sleeve, and then angularly bent to form a terminal portion extending angularly from said prong-engaging portion, the strands of said prong-engaging portion having tensioned engagement with the opposite sides of said extensions.

BENGT J. JOHANSON.
